(57) **CLAIM**

The ornamental design for a landscape edging, as shown and described.

DESCRIPTION

FIG. 1 is a front isometric view of a landscape edging, showing a first embodiment of our new design;

FIG. 2 is a front elevational view of the landscape edging of FIG. 1;

FIG. 3 is a right side elevational view of the landscape edging of FIG. 1;

FIG. 4 is a rear elevational view of the landscape edging of FIG. 1;

FIG. 5 is a left side elevational view of the landscape edging of FIG. 1;

FIG. 6 is a top plan view of the invention of the landscape edging of FIG. 1;

FIG. 7 is a bottom plan view of the invention of the landscape edging of FIG. 1;

FIG. 8 is a top plan view thereof, showing the landscape edging of FIG. 1 in an alternate configuration of use;

FIG. 9 is a front isometric view of the landscape edging, showing a second embodiment of our new design;

FIG. 10 is a front elevational view of the landscape edging of FIG. 9;

FIG. 11 is a right side elevational view of the landscape edging of FIG. 9;

FIG. 12 is a rear elevational view of the landscape edging of FIG. 9;

FIG. 13 is a left side elevational view of the landscape edging of FIG. 9;

FIG. 14 is a top plan view of the invention of the landscape edging of FIG. 9;

FIG. 15 is a bottom plan view of the invention of the landscape edging of FIG. 9; and,

FIG. 16 is a top plan view thereof, showing the landscape edging of FIG. 9 in an alternate configuration of use.

The landscape edging is shown with a symbolic break in its length. The appearance of any portion of the landscape edging between the break lines forms no part of the claimed design. The broken lines immediately adjacent to the shaded areas represent portions of the landscape edging that form no part of the claimed design.
